PIN TUMBLER LOCK

Warren D. Kotab, Long Beach, Calif.
Application April 28, 1951, Serial No. 223,589

15 Claims. (Cl. 70—419)

1 This invention relates to locks of the pin tumbler type in which locking pins or tumblers are slidably mounted in two sets of pin bores, one of the sets of bores being in a stationary lock cylinder and the other set being in a cooperating plug rotatably mounted inside the fixed cylinder. When the matching key is inserted into a keyway leading into the interior of the plug, the locking pins are shifted to position the ends of the pins in alignment with the circumferential surface of the plug whereby the plug is released for lock-actuating rotation.

While locks of this type are well regarded as is evident in their wide use, it is a fact, nevertheless, that they can be opened without the use of a key. It is often not too difficult to pick a pin tumbler lock of the prevailing type simply by exerting a slight turning pressure on the plug and simultaneously applying a suitable instrument through the keyway to manipulate the locking pins.

The present invention is directed especially to the problem of constructing such a lock in a manner to make unauthorized tampering extremely difficult if not to make the lock completely pick-proof. This problem is met by a unique keyway arrangement that makes the locking pins practically inaccessible through the keyway except by means of the key that matches the lock.

The keyway arrangement includes relatively movable parts forming different portions of the keyway whereby one part may be manually moved relative to another part to change the keyway from a first key-receiving configuration to a second configuration and vice versa. The first keyway configuration provides a simple straight passage into the region of the locking pins and the second configuration provides a tortuous and more restricted passage that makes the inner region of the locking pins accessible only with extreme difficulty.

Incorporated in this arrangement is a suitable guard element controlled by relative movement of the keyway-forming parts in such manner that the guard element automatically cuts off the keyway from the locking pins whenever the keyway assumes the first mentioned configuration of a simple straight passage. Thus, the locking pins are protected from tampering by the automatic guard element whenever the keyway is relatively open and at other times the locking pins are protected by the tortuousness of the keyway itself.

The key matching the lock is inserted when the keyway has the first configuration of a straight

2 passage and then the configuration is changed to the tortuous configuration whereupon the automatic guard element automatically shifts position to make the locking pins accessible for operation by the key. It is apparent that to make this mode of operation possible the two keyway configurations must have portions in common. In other words, there must be a portion of the passageway that does not change in the shift from one configuration to the other and the key must conform to this unchanging portion.

In the preferred practice of the invention the keyway is formed in part by a body fixed to the rotatable plug and in part by what may be termed a guard member that is rotatably mounted adjacent the plug and preferably coaxial therewith. The plug and the associated body, which body may be an integral part of the plug, are concealed by the guard member. The guard member extends to the exterior of the lock and is adapted for convenient manual manipulation to change the configuration of the keyway.

The various features and advantages of the invention may be understood from the following detailed description taken with the accompanying drawings.

In the drawings, which are to be regarded as merely illustrative,

Figure 1 is a perspective view of a preferred embodiment of the lock as seen from the front and side;

Figure 2 is an enlarged view of the lock partly in section and partly in perspective;

Figure 3 is a perspective view on the same scale of the guard member as seen from the side and rear;

Figure 4 is a longitudinal sectional view of the lock with the parts positioned to give the keyway its first or key-receiving configuration;

Fig. 5 is a transverse section taken as indicated by the line 5—5 of Figure 4;

Figure 6 is an enlarged fragmentary sectional view showing the locking pins or tumblers at their inner limit positions locking the plug to the surrounding fixed lock cylinder;

Figure 7 is a longitudinal sectional view similar to Figure 4 showing the parts in position to give the keyway its second configuration forming a tortuous passage into the interior of the lock;

Figure 8 is a transverse section taken as indicated by the line 8—8 of Figure 7.

The principal parts of the preferred form of the invention shown in the drawings include a cylindrical housing or fixed lock cylinder 10, a

plug 11 rotatably housed in the lock cylinder, a circular body 12 fixedly mounted inside the plug 11, and what may be termed a guard member 13 that is rotatably mounted adjacent the plug and carries a guard element 14 in the form of a curved blade.

The cylindrical housing or fixed lock cylinder 10 may be of any suitable construction adapted for mounting in a door or the like. In the construction shown the lock cylinder 10 has an inner cylindrical wall 18 and a front wall 19 with a circular opening 20 therein. At the top of the inner cylindrical wall 18 is a series of radially upwardly extending pin bores 21.

The plug 11 has a cylindrical wall 23, a rear end wall 24, and the usual shank or operating shaft 25 for actuating the lock bolt (not shown). The cylindrical wall 23 is provided with a series of pin bores 26 positioned to register with the previously mentioned pin bores 21 in the fixed lock cylinder 10.

Slidably mounted in the matching pin bores 21 and 26 is an upper set of locking pins or tumblers 27 and a corresponding lower set of the locking pins or tumblers 28. The upper locking pins 27 are continuously urged downward or radially inward by suitable springs 29 in the well known manner. Preferably the lower or inner ends of the lower locking pins 28 are provided with laterally extending feet 30 that are of curved configuration as shown and terminate in points or toes 31.

As best shown in Figure 5, the inner surface of the cylindrical wall 23 of the lock plug 11 is formed with suitable grooves 35 into which the feet 30 may be lifted, there being one such groove for each of the lower locking pins 28. In like manner the circumferential surface of the circular body 12 inside the plug 11 is formed with corresponding grooves 36 into which the feet 30 may be lowered as indicated in Figure 8. The grooves 35 and 36 may be termed outer and inner grooves respectively.

It is contemplated that suitable means may be provided either to indicate when the plug 11 is positioned with the pin bores 26 in register with the pin bores 21 and/or to tend to maintain the plug in this relative position. By way of example, the drawings show a yielding latch means in the form of a small ball 37 mounted in a radial bore 38 in the periphery of the plug 11 and urged outward by a suitable spring 39 in the bore. When the pin bores 26 of the plug 11 register with the pin bores 21 of the cylindrical housing 10, the small ball 37 yieldingly seats in a shallow latching recess 40 in the cylindrical housing 10, as best shown in Figure 5.

The circular body 12 is fixedly secured to the plug 11 by two pins 43 as indicated in Figures 4 and 5 so that the plug and circular body are unitary with each other and may be regarded as constituting a single plug structure. It is contemplated that there will be sufficient space between the circumference of the circular body 12 and the surrounding cylindrical wall 23 of the plug 11 to receive the curved guard element 14 and to permit the guard element to be shifted around at least a portion of the circumference of the circular body. For this purpose the cylindrical wall 23 of the plug is cut away to provide an arcuate clearance space 44 which, as shown in Figure 5, terminates at one of its ends in a shoulder 45 and terminates at its other end in a shoulder 46. It will be noted in Figure 8 that when the feet 30 of the locking pins 28 are positioned in

the inner grooves 36 in the periphery of the circular body 12, the toes 31 of the feet extend outward across the arcuate space 44 in the path of the guard element 14 so that the guard element may slide under the feet and lift the pins with a cam action, thereby to position the feet in the outer grooves 35 of the plug 11 as shown in Figure 5.

For the purpose of forming a portion of the keyway into the plug 11, the circular body 12 is formed with a longitudinal radial slot 50 and preferably is also formed with an axial bore or passage 51 in communication with the slot.

The guard member 13 is rotatably mounted in the circular opening 20 in the fixed lock cylinder 10 and has a radial shoulder 52 slidably engaging the end wall 19 of the lock cylinder. The curved blade-like guard element 14 is an integral part of the guard member 13 and extends longitudinally inward from the shoulder 52.

The guard member 13 cooperates with the circular body 12 to form the keyway of the lock and for this purpose is formed with an axial bore or passage 55 and a longitudinal radial slot 56 extending from the axial passage almost but not quite to the periphery of the guard member. As best shown in Figure 3 the radial slot 56 is directed centrally of the guard element 14. Preferably the guard member 13 is formed with an inner extension in the form of a tubular well 58 that extends into and is journaled by the axial bore or passage 51 in the circular body 12. As best shown in Figure 4 the tubular wall 58 which forms the inner end of the axial passage 55 has a slot 59 that is an extension of the radial slot 56. The portion of the guard member 13 that protrudes outward from the cylindrical housing 10 has a knurled surface 60 to serve as a convenient manually operable knob.

Figures 4 and 5 show the guard member 13 turned to what may be termed its key-receiving position relative to the circular body 12. At this position the keyway has what may be termed a key-receiving configuration, the keyway being a straight passage into which a key may be inserted. This passage comprises the two central bores or passages 51 and 55 of the circular body 12 and guard member 13, respectively, together with the slot 50 of the circular body in registration with the slots 56 and 59 of the guard member.

When the guard member 13 is rotated to any appreciable extent from the position shown in Figures 4 and 5 the keyway changes from the configuration of a straight passage to the configuration of a tortuous passage. For example, in Figures 7 and 8 showing the guard member 13 rotated 180° from the position shown in Figures 4 and 5, the slot 56 being out of register with the slot 50 terminates in a blank wall formed by the end face of the circular body 12 and the tubular wall 58 extending inwardly from the guard member cuts off direct radial communication from the axial bore or passage 55 of the guard member to the slot 50 in the region of the inner ends of the locking pins 28.

The portion of the keyway that remains unaffected by rotation of the guard member 13 comprises the axial bore or passage 55 through the guard member, the remaining portion of the axial bore or passage 51 in the circular body 12 and the radial slot 50 in the circular body. As best shown in Figure 7, the key 61 for use with the lock conforms to this unchanged portion of the keyway in the sense of being dimensioned to lie within the confines thereof. It will be

noted that the key 61 has a straight shank 62 and the head or operating end 63 of the key is recessed or cut away as indicated at 64 to clear the tubular wall 58 so that the key has an overall angular configuration.

The operation of the lock may be readily understood from the foregoing description. Assuming that the plug 11 is interlocked with the cylindrical housing 10 by the locking pins 27 and 28, the position of the locking pins will be determined by the position of the guard element 14. If the guard member 13 is at the rotary position spacing the guard element 14 away from the region of the locking pins, as shown in Figures 2 and 6, the locking pins will be supported by the circular body 12 with the feet 30 of the locking pins seated in the inner grooves 36 in the periphery of the circular body. At these lower limit positions of the locking pins, the upper set of locking pins 27 extend from the cylindrical housing 10 partially into the plug 11 thereby locking the plug against rotation relative to the cylindrical housing.

If, on the other hand, the guard member 13 is rotated to place the guard element 14 under the locking pins, as shown in Figures 4 and 5, with the feet 30 of the locking pins displaced upwardly into the outer grooves 55 in the plug 11, the lower set of locking pins 28 will extend upward from the plug 11 partially into the cylindrical housing 10 to lock the plug against rotation relative to the cylindrical housing. Thus, there are two limit locking positions for the two sets of locking pins 27 and 28. There is no possibility of the guard element 14 unlocking the plug 11 by its cam action against the feet 30 to raise and lower the two sets of locking pins, because the abutting ends of the two sets of locking pins are staggered to cross the parting line between the plug and the cylindrical housing at different times. Thus, in the transition between the two limit locking positions caused by the cam action of the guard element 14, there is always at least one pin interlocking the plug and cylindrical housing.

If a person attempting to pick the lock rotates the guard member 13 to the position shown in Figures 4 and 5 for access into the interior of the plug, the guard element 14 will be automatically positioned across the inner ends of the locking pins, thereby cutting off access to the locking pins. If the guard member 13 is rotated to remove the guard element 14 from the region of the locking pin, the keyway automatically changes to the tortuous angular configuration shown in Figure 7 and thereby makes the locking pins to all practical purposes inaccessible for unauthorized manipulation through the keyway.

To unlock the lock, the guard member 13 is rotated to the key receiving position shown in Figure 4 to provide a straight passage through which the key may be inserted to the operating position shown in dotted outline in Figure 4. In practice the key may be partially inserted for the purpose of rotating the guard member 13 into the key receiving position and then the inward movement of the key may be completed. It will be noted in Figure 4 that at this time the guard element 14 is under the locking pins and holds the locking pins at their outer limit positions. The guard member 13 is then rotated to the position shown in Figure 7 or at least sufficiently to carry the guard element 14 away from the feet 30 of the locking pins.

The removal of the guard element 14 from the 75

region of the locking pins permits the locking pins to drop downward from their upper limit locking position under pressure from the springs 29, but now the locking pins do not drop to their lower limit locking positions shown in Figure 6 because the key 61 stops the downward movement of the locking pins at the positions shown in Figure 7. It can be seen in Figure 7 that the mutually contacting faces of the two sets of locking pins 27 and 28 coincide with the periphery of the plug 11 so that the plug is now free to rotate relative to the cylindrical housing 10. The plug 11 may be rotated to its unlocked position simply by turning the key 61, the key turning the circular body 12 which is connected to the plug 11 by the pins 43.

To again lock the lock, the key 61 is used to rotate the plug 11 until the yielding latch in the form of the ball 37 seats in the latching recess 40, thus placing the pin bores of the plug in registration with the corresponding pin bores in the cylindrical housing 10. The guard member 13 is then rotated to shift the guard element 14 under the locking pins thereby lifting the locking pins to their upper limit locking position shown in Figures 4 and 5. This rotation of the guard member 13 brings the slot 56 in the guard member into registration with the slot 59 in the circular body 12, thereby forming the straight passage shown in Figure 4 through which the key 61 may be withdrawn.

My disclosure in specific detail of a preferred embodiment of the invention will suggest to those skilled in the art various changes, modifications, and other departures from the disclosure that properly lie within the spirit and scope of my appended claims.

Having described my invention, I claim:

1. A lock combination comprising: a stationary lock cylinder with a first set of radial pin bores; a first means in the form of a plug rotatably mounted in said cylinder, said plug having a second set of radial pin bores positioned to register with said first set at a locking position of said plug relative to said cylinder, said plug having an axial bore and a slot extending radially from the bore; two sets of spring-pressed locking pins in said two sets of pin bores respectively; a second means having an axial bore and a radial slot to cooperate with the bore and slot of said first means to form a keyway into said plug, said first and second means being adapted for relative movement for manually varying the configuration of the keyway from a first configuration affording relatively free access to the region of the registered pin bores to a second configuration of less accessibility; and means responsive to said relative movement of said first and second means to cut off the registered pin bores from said keyway when said keyway is changed to said first configuration.

2. A lock combination as set forth in claim 1 in which said first and second configurations of the keyway have axial portions in common to accommodate the axial portion of a key.

3. A lock combination as set forth in claim 1 in which said first configuration provides a substantially straight passage from the exterior to the region of the second set of pin bores and said second configuration provides a tortuous passage.

4. A lock combination as set forth in claim 3 which includes a key that is insertable through said straight passage but conforms to said tortuous passage.

5. A lock combination as set forth in claim 1

in which one of said first and second means has an exposed knob portion for manual manipulation.

6. A lock combination comprising: a stationary lock cylinder with a first set of radial end bores; a plug structure rotatably mounted in said cylinder, said plug structure having a second set of radial pin bores positioned to register with said first set, said plug structure having a first longitudinal slot communicating with the inner ends of said second set of pin bores; spring-pressed locking pins in said pin bores; and a manually operable guard member rotatably mounted in said cylinder to cooperate with said plug structure to form a keyway which varies in configuration with rotation of the guard member relative to the plug structure, said guard member having an axial passage and a second longitudinal slot, said guard member being movable to a key-receiving position at which said second slot registers with said first slot and being movable therefrom to a second position with said second slot out of register with the first slot, said guard member having a guard element positioned to register with said pin bores to cut the pin bores off from said first slot at said key-receiving position of the member and to be out of register with the pin bores at said second position of the member.

7. A lock combination as set forth in claim 6 which includes a key conforming to the configuration of said keyway at said second position of the guard member.

8. A lock combination as set forth in claim 6 in which said guard member has an inner tubular wall extending into said plug structure and forming the inner end of said passage, said tubular wall having a radial slot continuing said second slot whereby said tubular wall cuts off a portion of said first slot at said second position of the guard member.

9. A lock combination as set forth in claim 8 in which said guard member is coaxially journaled in said plug structure.

10. A lock combination as set forth in claim 6 in which said guard element is a blade curved concentrically of the plug structure and in which the plug structure provides a correspondingly curved clearance space for travel of the guard element into and out of register with said pin bores.

11. A lock combination as set forth in claim 6 which includes means to yieldingly latch said plug structure in position with said two sets of pin bores in registration with each other.

12. A lock combination as set forth in claim 6 in which includes a key; in which said locking pins in the absence of a key are free to move to inner locking positions under spring pressure when said guard element is out of register with

5

the pin bores; in which said key is dimensioned to displace said locking pins outward from said inner locking position to intermediate release positions; and in which said guard element when in register with said bores displaces said pins to outer locking positions.

13. A lock combination as set forth in claim 6 in which said locking pins have laterally extending feet for contact with cooperating surfaces of said plug structure to limit the inner movement of the pins and said feet are shaped as cams for outward movement of the pins by said guard element.

14. A lock combination comprising a stationary lock cylinder with a first set of radial pin bores; a plug with a cylindrical wall rotatably mounted in said cylinder, said cylindrical wall having a second set of radial pin bores positioned to register with said first set; spring-pressed locking pins in said pin bores; a circular body inside said plug and fixedly connected with the plug, the periphery of said body serving as a stop to limit the inward movement of said pins, said body having a longitudinal slot communicating with said second set of pin bores, said body and said cylindrical wall of the plug forming a concentric clearance space extending at least partially around the circular body; a manually operable guard member rotatably mounted in said cylinder coaxially

15 20 25 thereof to cooperate with said body to form a keyway which varies in configuration with rotation of the guard member relative to said body, said guard member having an axial passage and a second longitudinal slot extending from the passage toward the periphery of the member, said guard member being movable to a key-receiving position at which said two slots register with each other and being movable through a range of other positions with the two slots out of register with each other but with said passage in communication with said first slot, said guard member having a concentrically curved guard blade in said space positioned to cut off said pin bores when the member moves out of said range of positions into said key-receiving position.

15. A lock combination as set forth in claim 14 in which said locking pins have cam elements both for contact with said body and for cooperation with said blade and in which grooves are provided both in said body and in said cylindrical wall to receive said cam elements.
